[57] ABSTRACT

An improved hinge assembly for mounting a discharge door on the front wall of a large bin capable of transporting and storing bulk material. The hinge assembly consists of a generally S-shape hinge bar which is secured to the front wall of the bin and terminates at its lower end in a plurality of depending generally U-shape supports which are spaced apart in a horizontal direction. A hinge rod which supports the door is rotatably supported in the depending supports on the hinge bar.

ATTORNEYS

DOOR HINGE ASSEMBLY FOR BINS

This invention relates generally to large metal bins of a type for transporting and storing bulk materials, an example of which is illustrated in U.S. Pat. No. 2,648,428 owned by the assignee of this application. Such a bin includes a large rectangular discharge opening in the bin front wall adjacent the lower end of the bin, and a door for closing the discharge opening. The door is conventionally supported on a hinge which consists of interfitting tubular portions on the bin front wall and the bin door and a hinge rod which extends through the tubular portions. It is an object of the present invention to provide an improved door hinge assembly for bins of this type.

It is a further object of this invention to provide a door hinge assembly for bins of the above type which has improved sanitary features, namely, is less likely to become contaminated and is easier to clean.

Still another object of this invention is to provide a door hinge assembly for bins which is of simple and inexpensive construction.

In the door hinge assembly of this invention, a generally S-shape hinge bar is secured by welding to the front wall of the bin at a position above the discharge opening. The S-shape construction of the hinge bar enables it to be welded at two locations to the front wall of the bin so that it will provide a firm support for a hinge rod secured to the door. The hinge rod is attached to upwardly extending finger portions on the door which are located between depending supports on the hinge bar so that a relatively open construction is achieved which is readily cleaned.

Further objects, features and advantages of this invention will become apparent from a consideration of the following description, the appended claims, and the accompanying drawing in which:

FIG. 1 is a foreshortened front view of a bin provided with the improved door hinge assembly of this invention;

FIG. 2 is a fragmentary enlarged sectional view of a portion of the hinge assembly of this invention as seen from substantially the line 2-2 in FIG. 1; and

FIG. 3 is an enlarged fragmentary sectional view of another portion of the door hinge assembly of this invention as seen from the line 3-3 in FIG. 1, showing the bin door in closed positions in solid lines and in open positions in broken lines.

With reference to the drawing the door hinge assembly of this invention, indicated generally at 10, is illustrated in FIG. 1 applied to a bin 12 having a top wall 14, a front wall 16, and a bottom wall 18. The front wall 16 has a discharge opening 20 formed therein which is of generally rectangular shape and is closed by a rectangular door 22 during transport and storage of bulk material in the bin 12. The door 22 is maintained in a closed position by a latch mechanism (not shown) which is disposed on the inside of the door 22 at the lower end thereof and is shown in detail in the aforementioned U.S. patent.

The door hinge assembly 10 includes a hinge bar 24 which extends generally horizontally of the front wall 16 at a position

above the discharge opening 20. The bar 24 is secured to the front wall 16 by continuous lines of welding 26 and 28 which extend horizontally at vertically spaced positions on the front wall 16 and the hinge bar 24. At its lower end, the hinge bar 24 includes a plurality of horizontally spaced generally U-shape support portions 30 which give the bar 24 a generally S-shape configuration at the supports 30 as shown in FIG. 2. A hinge rod 32 is rotatably supported in the supports 30 and is connected to the door 22 by downwardly extending finger portions 34 which are located between and spaced from the supports 30. The rod 32 is secured to the fingers 34 by means of welding 36 (FIG. 3).

It can thus be seen that the door 22 is readily opened by moving it along an arcuate path extending upwardly and outwardly, as shown in broken lines in FIG. 3, so that the hinge rod 32 rotates in the hinge bar support portions 30. When the door 22 is closed, a seal 38 carried by the door engages the bin front wall 16 at a position surrounding the opening 20 so as to prevent leakage around the door 22. By virtue of the relatively open construction of the hinge assembly 10, contamination of the hinge assembly by foreign material which might fall into material being discharged through the door opening 20 is avoided. By virtue of the welding 26 and 28, the hinge bar 24 is in a somewhat sealed relation with the bin front wall 16 so as to avoid contaminants being carried on the hinge bar 24. Furthermore, the hinge assembly 10 is readily manufactured by stamping the hinge bar 24 and welding the hinge rod 32 to the door 22. This avoids any requirement for extrusions.

What is claimed is:

1. In a bin having an upright front wall provided with a discharge opening adjacent the lower end of said wall, and a substantially rectangular door for said discharge opening, the improvement comprising a hinge bar extending substantially horizontally and secured to said front wall at a position above said opening, said bar having a plurality of depending generally U-shape supports spaced apart horizontally and disposed above said opening, said U-shape supports opening upwardly and being externally accessible to facilitate cleaning thereof, and a substantially straight hinge rod secured to said door and rotatably supported in and engaged with said U-shape supports in the closed position of said door whereby said door is hinged movable about a substantially horizontal axis extending along said rod, upward movement of said rod in said supports being unrestricted to thereby provide an open hinge construction for said door which is readily cleaned.

2. A bin according to claim 1 wherein said hinge bar is of generally S-shape in vertical section at said supports and further including substantially horizontally extending weld means extending along the upper and lower portions of said hinge bar securing said hinge bar to said front wall.

3. A bin according to claim 2 wherein said hinge rod is secured to said door by extension means on said door extending upwardly therefrom between said U-shape supports.
